UNITED STATES PATENT OFFICE.

JOHN E. ALEXANDER AND WALTER G. GEHRS, OF PORT EDWARDS, WISCONSIN.

PLATE ATTACHMENT FOR EXHAUST MANIFOLDS.

Application filed December 5, 1921. Serial No. 519,855.

To all whom it may concern:

Be it known that we, JOHN E. ALEXANDER and WALTER G. GEHRS, citizens of the United States, and residents of the city of Port Edwards, in the county of Wood and State of Wisconsin, have invented certain new and useful Improvements in a Plate Attachment for Exhaust Manifolds; and we do hereby declare that the following is a full, clear, and exact description of the same, reference being had to the accompanying drawings, and to the numerals of reference marked thereon, which form a part of this specification.

15 This invention relates to improvements in attachments for automobile engines especially adapted for use with the carburetor and intake manifold of the same.

One of the objects of this invention is the 20 provision of means which may be readily applied to any automobile having the intake and exhaust pipes on the same side of the engine and which will act to heat the intake manifold by means of the heat radiated 25 from the exhaust pipe whereby a better combustion mixture will be obtained.

Another object of this invention is the 30 provision of a heating device for automobile manifolds which is especially adapted for use with automobiles and which may readily be applied thereto with a minimum of trouble and without the necessity of any extra parts.

Another object of this invention is to provide a housing for the manifolds which can be made of sheet metal by stamping.

A still further object of this invention is the provision of a unitary device adapted to be used in connection with separate exhaust 40 and intake manifolds whereby the same may be made to function as a unit and the heat radiated from the exhaust pipe during the operation of the engine be directly transferred to the intake manifold to better vaporize the incoming mixture.

Still another important object of this invention is the provision of an auxiliary heating device for internal combustion engine manifolds which shall be simple of construction 50 and readily and cheaply manufactured whereby the same may be used with a minimum of expense, and which article moreover is of neat appearance and can be applied by anyone within a very short space of

time and with practically no trouble or labor. 55

Another important object of this invention is to provide a casing to fit over the intake and exhaust manifolds of an engine and to furnish such a casing with a means for heating these manifolds when the engine is 60 cold.

It is a further object of this invention to so locate the supplemental heating means that the heat supplied thereby will be confined by the casing and conducted to the 65 manifolds.

Other and further important objects of this invention will be apparent from the disclosures in the accompanying drawings and the following specification.

70 The invention (in a preferred form) is illustrated in the drawings and hereinafter more fully described.

On the drawings:

Figure 1 is a side elevation of an automobile engine of the Ford type showing the improved device of this invention as applied thereto.

Figure 2 is an inside view of the attachment.

80 Figure 3 is a top view of the same.

Figure 4 is an end view of the device.

Figure 5 is an enlarged sectional view of the heating device taken on the line 5—5 of Figure 4.

85 As shown on the drawings:

The reference numeral 10 indicates an automobile engine having an exhaust pipe 12 and an intake manifold 14 thereon of ordinary construction.

90 The intake and exhaust manifolds are covered with a casing 16 of sheet metal or other sheet material. This casing has a main face 17 which slopes upward and backward in order to afford space for the valve cover 95 below and closely fit the engine block above. The edges of this casing are made by flanges 18 each of which has a shoulder 19 to fit the shoulder of the engine block. The edges of the face 17 which are furnished with 100 these flanges are oblique but a vertical edge at the upper end of one flange 17 also has a flange 20 intended to fit against the cylinder head behind the outlet manifold as shown at the left in Figure 105 1. The upper part of the opposite edge of the face 17 is curved as shown at 21 to fit the curve of the exhaust pipe as shown at

the right in Figure 1. At the upper end of the flange 20 the edge of the face 17 has a shoulder 22 and then a curved portion 23 which accommodate the seat of the left hand bolt 28 and fit the shape of the exhaust manifold. The straight edge connecting the curved corners 21 and 23 lies against the side of the exhaust pipe along the length thereof.

10 The bolts 28 are those which attach the manifolds to the cylinder head. Three of these pass through the holes 26 in the casting 16 but the fourth or left hand one in Figure 1 passes outside the flange 20. The 15 clamps 30 which are provided to enable the bolts 28 to hold the manifolds in place are located on the outside of the casing and serve to hold the casing in place also.

In order that the upper part of the face 20 17 may lie flat against the exhaust manifold, there is an angle between it and the oblique part as shown at 24.

The two flanges 18 do not meet at the bottom of the device but are separated by 25 a small distance. The edges of this space are rounded as shown at 31 in order to fit well against the intake manifold just above the carburetor as shown at 32 in Figure 1. The inner part of the passage between the 30 flanges 18, which is the lower part in Figure 3, is occupied by a box 33. The outer and inner sides of this box are single walls of sheet metal but the other two side walls are made double as shown at 34 in Figure 5, 35 and the upper parts of these walls are turned parallel to flanges 18 to afford flanges 35 and 36 above and below the flanges 18 respectively. The box can be secured to the casing by sliding it into place, the 40 flanges 35 and 36 clasping the lower edges of the flanges 18.

In the bottom of the box is placed asbestos or other absorbent material as shown at 37 and this is secured in place by having a 45 piece of wire gauze 38 pressed down over it. The gauze fits the sides of the box closely enough to hold it against the asbestos. A hole 39 in one of the double sides of the box affords access to the absorbent.

50 In order to attach the casing to an engine, the box 33 is first slipped out. Then the nuts are removed from the bolts 28 and the clamps 30 removed. The casing is then placed on the engine, the passage 40 being slipped over the intake manifold and the holes 26 over three of the bolts. The clamps 30 and the nuts are then replaced and the nuts tightened. Finally the box 33 is slipped into the outer part of the passage 55 40. The outside of the casing may be japanned or lacquered, as desired.

60 It will be seen that herein is provided an attachment for automobile engines which may be readily applied and which is of very 65 inexpensive construction and may be man-

ufactured in great quantities by an ordinary stamping process, thereby rendering it readily adaptable for use upon all engines which are equipped with separate exhaust and intake manifolds by only slight variations in 70 the shape thereof.

When the engine is running, the exhaust manifold is hot. The effect of the casing 75 16 is to confine the heat, radiated from the exhaust manifold, to a space containing the intake manifold. This heats the intake manifold with heat that would otherwise be wasted and so increases the efficiency of the engine.

The great saving of fuel will be apparent 80 from the use of this device, as the same is more readily vaporized on account of the heat which is directly conveyed to the intake manifold from the exhaust pipe by means of this arrangement.

85 When the engine is not running and the heat that should come from the exhaust manifold is lacking, it is desirable before attempting to start the engine that the temperature of the inlet manifold be raised. For 90 this purpose the operator puts some gasoline, alcohol or other inflammable liquid on the absorbent material 37 and sets fire to it. This is most conveniently done by using a can like an oil can to introduce the inflammable liquid through the hole 39 and then thrusting a lighted match through the same hole. As the liquid thus introduced burns, the heat generated is confined within the casting 16 and so goes almost wholly to raise the 95 temperature of the manifolds. The intake manifold is thus brought to a temperature that insures the vaporization of the gasoline drawn from the carburetor and so makes easy and certain the starting of the engine. 100

105 Heretofore, only the more expensive automobiles have been equipped with integral intake and exhaust manifolds, owing to the difficult and costly construction, but by means of this device, the carburetors on the 110 cheaper grades of cars can be made to operate as efficiently as if employed with the more expensive double manifold.

We are aware that many changes may be made and numerous details of construction 115 varied throughout a wide range without departing from the principles of this invention, and we therefore do not purpose limiting the patent granted hereon otherwise than necessitated by the prior art.

120 We claim as our invention:

1. An auxiliary heating means for an intake manifold comprising a unitary sheet metal plate having holes in the plate adapted to co-operate with clamping bolts upon the engine and integral inwardly turned flanges extending around portions of the edge of said plate, said flanges formed to co-operate with portions of the engine adjacent the intake manifold to snugly house the 125 130

same, the upper ends of said inwardly turned flanges being formed to correspond to the shape of the exhaust manifold at the points where the same contacts with said heating means.

2. A V-shaped casing adapted to fit an automobile engine and confine the heat radiated therefrom, a holder for fuel at the bottom of said casing and said casing having a hole through which fuel may be introduced into said holder, and means integral

with said fuel holder for detachably securing it to the casing.

In testimony whereof, we have hereunto subscribed our names in the presence of two 15 subscribing witnesses.

JOHN E. ALEXANDER.
